DELIVERY MECHANISM FOR BOTTLE CAP ASSEMBLING MACHINES

Filed Feb. 10, 1922

2 Sheets-Sheet 2

Fig. 4.

UNITED STATES PATENT OFFICE.

BERTHOLD NAGY, OF BROOKLYN, NEW YORK.

DELIVERY MECHANISM FOR BOTTLE-CAP-ASSEMBLING MACHINES.

Application filed February 10, 1922. Serial No. 535,634.

To all whom it may concern:

Be it known that I, BERTHOLD NAGY, a subject of the King of Hungary, residing at the borough of Brooklyn, in the city of New York, county of Kings, and State of New York, have invented certain new and useful Improvements in Delivery Mechanisms for Bottle-Cap-Assembling Machines, of which the following is a specification, reference being had therein to the accompanying drawings, which form a part thereof.

My invention relates to delivery mechanisms for bottle cap assembling machines, and more particularly to a construction and arrangement of parts which will permit a slow movement of the completely assembled caps adjacent the finishing head of the machine, without reducing the capacity of the machine.

Heretofore in bottle cap assembling machines, it has been a common practice to provide a belt conveyer adapted to receive the completely assembled caps as they are delivered from the finishing head, and convey them for substantially the full length of the machine, said caps being transferred in groups, to a slow moving belt at the end of the machine adjacent the shell hopper and most remote from the finishing head, where they may be readily inspected and imperfect caps removed.

The difficulty with this type of machine has been that, owing to the slow moving inspection belt being remote from the mechanisms for assembling the cork disk and shell in the machine, and the finishing head, two operators have been required, one to observe the functions of the mechanisms of the machine proper, and the other to inspect the completed product.

In a delivery mechanism embodying my invention, the various parts of the delivery mechanism are so constructed that they may be conveniently assembled in an ordinary bottle cap assembling machine, adjacent the delivery head end of the machine so that one operator may inspect the caps after their delivery from the head, and observe the assembling mechanisms of the machine, while in a position where the controls of the machine will be conveniently accessible so that in an emergency the machine may be instantly stopped.

To secure the desired result, and to adapt the delivery mechanism to existing assem-

bling machines and yet permit the operator to be sufficiently close to all of the mechanisms in the manner above described, means for actuating the delivery mechanism must be compactly arranged and the speed of the various parts thereof so synchronized as to secure a proper timing thereof with relation to each other and to the functioning of the machine in assembling the caps.

A delivery mechanism embodying my invention includes a high speed conveyor adapted to receive completely assembled caps as they are discharged from the finishing head, and to remove them from adjacent the head sufficiently rapidly to always provide space for the cap delivered to the conveyor upon the succeeding delivery movement of the finishing head, intermittently operative means being provided whereby when a certain number of caps have been accumulated upon said conveyor, they will be automatically delivered to a slow moving conveyor, the speed of which will be such as to permit a convenient inspection of the caps and yet have a capacity commensurate with the full capacity of the finishing head.

All of the parts of the delivery mechanism are actuated from a single shaft, thus ensuring a perfect timing in the functioning of this mechanism, this shaft receiving its power from the main shaft of the machine so as to time the delivery mechanism with relation to the functioning of the delivery head.

The invention consists primarily in a delivery mechanism for bottle cap assembling machines embodying therein a narrow, high speed conveyor belt extending laterally of an assembling machine and adapted to receive completely assembled caps one at a time from the finishing head of said machine, a wide, low speed conveyor belt moving at right angles to the direction of movement of high speed belt and having one end thereof closely adjacent thereto, means adapted to simultaneously actuate said belts, a transfer device above said high speed belt, and means for intermittently actuating said transfer device, whereby caps upon said high speed belt will be simultaneously removed therefrom in groups and delivered to said low speed belt; and in such other novel features of construction and combination of parts as are hereinafter set forth and described, and more particularly pointed out in the claims hereto appended.

Referring to the drawings,

Fig. 1 is a condensed plan view of a delivery mechanism embodying my invention;

Fig. 2 is a section of one end of the power shaft for the low speed belt, showing the actuating means therefor and for the transfer device;

Fig. 3 is a side view of the delivery mechanism partly broken away;

Fig. 4 is an end view thereof; and

Fig. 5 is a section on an enlarged scale, on the line 5—5 of Fig. 1.

Like numerals refer to like parts throughout the several views.

In the embodiment of my invention illustrated in the drawings, I have shown at 10 a fragmentary portion of a bottle cap assembling machine including therein a rotatable finishing head 11 having a sequence 20 of plungers adapted to apply a continuing pressure to a cap after the shell and cushion disk have been applied thereto. In this type of machine, the assembled cap is delivered to the finishing head, and after it 25 has been subjected to pressure for the desired length of time measured by substantially one full rotation of the head, the completed cap is ejected from the head. This mechanism is old and well known in this art and forms no part of my present invention, excepting in so far as it is necessary to synchronize the functionings of the delivery mechanism with the angular speed of the head so as to remove the completed 30 caps from adjacent said head with sufficient rapidity to impart to the delivery mechanism a capacity commensurate with the other mechanisms of the machine including said head.

To secure the desired handling of the caps after leaving the head 11, I provide a high speed conveyor belt 12 passing about a power shaft 13 and roller 14, said shaft and said roller being mounted in a frame 45 15 secured to the frame of the machine, in any desired manner, and forming a lateral extension thereof, closely adjacent the finishing head so that the caps as they leave the finishing head will be delivered to said belt and be conveyed from adjacent the head. To avoid any such sagging of the upper reach of the belt 12, as would tend to cause movement of the caps along the belt, I provide a support 16 engaging the 50 under side of the upper reach which will ensure the top reach of the belt remaining substantially flat at all times.

Also carried by the frame 15, are rollers 60 17 and 18, the axes of which are parallel with each other but at right angles to the axes of the shaft 13 and roller 14. Extending about said rollers 17 and 18 is a wide, low speed conveyor belt 19 extending 65 parallel with the top frame of the machine longitudinally thereof and closely adjacent

thereto. While this belt 19 is relatively wider than the belt 12, its total width will be approximately eight or ten inches, so as to permit an operator standing beside same to still be sufficiently close to the working 70 mechanisms of the machine 10, to be able to inspect these mechanisms and control the operation of the machine, while at the same time inspecting caps delivered from the finishing head 11.

Intermediate the rollers 17 and 18, I provide parallel supports 20 and 21 which will serve to impart rigidity to the supporting frame 15 adjacent said low speed belt and prevent sagging of this belt in a manner 80 to cause relative movement of the caps in different rows. Carried by the roller 17 is a worm gear 22 co-operating with which is a worm 23 upon the shaft 13, a construction which ensures not only the desired reduction of speed in the drive of the belt 19, but the maintenance of a fixed ratio of speed between this belt and the belt 12 which is also driven from the shaft 13.

Carried by the shaft 13 is a gear 24 driven from the main shaft of the machine by means of the chain and sprocket wheel mechanism 25 and the intermediate gear 26 which ensures the desired direction of drive 90 of the shaft 13, at a speed so proportioned to that of the main shaft of the assembling machine as to cause the lineal speed of the belt 12 to substantially correspond with the angular speed of the finishing head 11.

Although the shaft 13 is small, it will be noted that a speed reducing mechanism is employed between this shaft and the main shaft of the machine which is necessary owing to the fact that while the delivery mechanism is driven from this main shaft, the lineal speed of the conveyor belt 12 is determined by the angular speed of the finishing head 11, which is of necessity relatively lower than that of the main shaft of the machine, since said finishing head makes only a small part of a revolution with each full revolution of said shaft.

Mounted upon the frame 15 immediately above the belt 12, and with its axis substantially in vertical alignment with the center line of said belt, is a transfer device adapted to have intermittent movement in a manner to simultaneously remove all caps upon the belt 12 and deliver them in a group to the belt 19, the functioning of said device being so controlled that it will operate twice with each full cycle of the belt 12 and will also be operated in synchronism with the movement of the belt 19 so as to avoid the piling of caps upon said last named belt in a position where proper and rapid inspection thereof is difficult or impossible.

This transfer device comprises a plurality of spaced vanes 27 carried by oppositely dis-

posed circular head plates 28 and 29, the plate 28 being of relatively smaller diameter than the plate 29 to permit the caps to pass freely below the plate 28 onto the 5 belt 12, the increased diameter of the plate 29 being for the purpose of imparting greater rigidity to said vanes. Said plates 28-29 are carried by a shaft 30.

The plate 29, which is more remote from 10 the finishing head 11, has secured thereto a ratchet wheel 31 co-operating with which is a pawl 32 carried by a swing arm 33 mounted upon the shaft 30, said pawl being adapted to be actuated by means of a crank 15 shaft 34 having an upwardly extending arm 35 pivotally connected by a link 36 with the swing arm 33. The crank shaft 34 also carries a cam 37 projected in the path of a sequence of tappets 38 carried by the worm 20 gear 22; the function of these tappets and cam is to merely set the pawl 32 in relation to the ratchet wheel 31, the feeding movement of the vanes 27 of the transfer device being imparted thereto by a weight 39 so as 25 to ensure ease of movement of said vanes and avoid a too rapid movement of the caps from the belt 12 to the belt 19.

Preferably I arrange the belt 19 upon a slightly lower plane than the belt 12 so as 30 to bring the upper reach of the former in close proximity to the latter, the gap between said belts being closed by a stay rod 40 having an inclined upper surface along 35 which the caps may freely glide after leaving the belt 12 and until they come to rest upon the belt 19.

The vanes 27 are spaced apart a distance in arc substantially equalling the width of the belt 12 and the outer edges of said vanes 40 come in sufficiently close proximity to said belt to form parallel guides between which the caps pass as they are being conveyed by the belt 12, thus precluding possibility 45 of escape of the caps from said belt and maintaining them in substantial alignment until they are moved from the belt by one of said vanes.

The belt 19 is of a width substantially equalling the length of the upper reach of 50 the belt 12 so as to receive caps in a number required to fill the said reach of the belt 12.

The operation of the herein described mechanism is substantially as follows:—

With each cycle of the main power shaft 55 of the assembling machine, a completely assembled cap is discharged from the finishing head 11, and falls upon the high speed belt 12, said belt and the low speed belt 19 being continuously actuated, but at different 60 speeds as described.

The slow movement of the worm gear 22 will, through a tappet 38 and cam 37, impart a gradual movement to the crankshaft 34, lifting the weight 39 and advancing the pawl 32 so as to cause it to ride upon the

succeeding tooth of the ratchet wheel 31, the shaft 30 during this movement remaining stationary with two of the vanes immediately above the belt 12 thus forming fixed guides between which the completely assembled caps pass with movement of the belt. The small diameter of the circular head plate 28 affords clearance between same and the belt 12 for the passage of said caps. Each cap as it is delivered to the belt 12 70 will be conveyed thereby away from the finishing head 11, at a speed so that upon the discharge of the next cap from said finishing head, there will be space upon the belt to receive same. 75

When the entire upper reach of the belt 12 is occupied by caps, and immediately following the delivery of the last cap which the belt will contain, the tappet 38 operative upon the cam 37 will pass from the rise of said cam, thus permitting the weight 39 to descend, rocking the shaft 34 in a direction opposite to its movement by said cam 37, and imparting such movement to the shaft 30 as will cause one of the vanes 27 to wipe all of the caps upon the belt 12 therefrom, the said shaft 30 coming to rest immediately thereafter with the succeeding vane 27 and the vane which has just been operative to wipe the caps from the belt, 80 in the desired guiding relation to the belt 12. 85

The caps which are indicated at *a* in the drawings, upon leaving the belt 12, slide down the inclined surface of the stay rod 40, and come to rest, in a line, upon the low speed belt 19, by which they will be conveyed slowly away from the belt 12. 90

A cap *a* will be delivered to the belt 12 with each cycle of the main power shaft of the machine 10, the vanes 27 being intermittently operated at intervals according to the number of caps which it is desired to simultaneously transfer to the belt 19, so that with the continued operation of said machine 10, the belt 19 will be substantially 100 completely covered with finished caps with the cork disks presented upwardly where an operator standing adjacent the finishing head 11 may conveniently inspect all of the caps upon said belt, and will have ample time to do so and, at the same time to watch the other mechanisms of the machine, excepting the shell feeding mechanism, which latter in actual practice requires little or no 110 attention excepting for the occasional refilling of the hopper. 115

In the embodiment of the invention shown, the belt 12 is of a length to receive eight caps while the shaft 30 is stationary, the ratio of the gears 24 and 26 and the diameter of the shaft 13 being so proportioned that with each cycle of the main power shaft of the machine, the belt 12 will be advanced a distance substantially equaling the diameter of a bottle cap, the speed 120 125 130

ratio between the belt 12 and the belt 19 being such that the latter belt will travel at substantially one-eighth the speed of the former.

5 By employing a shaft 13 carrying a driving pulley for the belt 12 and a worm meshing with the worm gear driving the belt 19, the timing of both belts is positive and invariable, so that there is little or no likelihood of a piling of the caps upon either of these belts.

By employing a rock shaft actuated from the power gear driving the belt 19, the timing of the actuation of the wiping vanes is 15 also made positive, the substantially instantaneous action of these vanes being secured through the actuation of the pawl 32 under the influence of the weight 39, or its equivalent, without imparting such a violent impulsive pulse to the caps as would tend to cause a loss in their alinement as they pass from the belt 12 to the belt 19. I secure highly advantageous results by setting the pawl 32 through the application of a slow, continuing power, since by this method accuracy in the timing of the operative moment of the pawl upon the ratchet wheel may thus be secured. By using a chain and sprocket mechanism 25, I avoid any possible loss in 30 synchronism between the main power shaft of the machine and the delivery mechanism such as might occur if a belt and pulley drive be used.

It is apparent that the design of the driving mechanism shown in the drawings, to 35 secure the desired speed ratio, is capable of wide variation so long as gearing is employed for driving the belts 12 and 19 at the desired speed with relation to each other 40 and the angular speed of the finishing head 11.

It is not my intention to limit the invention to the precise details of construction shown in the accompanying drawings, it 45 being apparent that such may be varied without departing from the spirit and scope of the invention.

Having described the invention, what I 50 claim as new and desire to have protected by Letters Patent, is:—

1. In connection with a bottle cap assembling machine comprising a rotary finishing head, the combination of a delivery mechanism consisting of a narrow conveyor belt 55 running with a speed substantially corresponding to the angular speed of the finishing head and being laterally disposed to the same so as to receive the assembled caps dropping from the said finishing head, a wire conveyor belt, running at lower speed than the narrow belt and at a right angle to the same, having one end closely adjacent to the narrow belt, means directly and simultaneously actuating said belts, an intermittently rotary transfer device above said

narrow belt, and means co-operatively connected with aforesaid belt actuating means for intermittently actuating said transfer device, whereby caps upon said narrow belt will be simultaneously removed therefrom 70 in groups and delivered to said wide belt.

2. In connection with a bottle cap assembling machine comprising a rotary finishing head, the combination of a delivery mechanism consisting of a narrow conveyor belt 75 running with a speed substantially corresponding to the angular speed of the finishing head and being laterally disposed to the same so as to receive the assembled caps dropping from the said finishing head, a wide conveyor belt, running at a lower speed than the narrow belt and at a right angle to the same, having one end closely adjacent to the narrow belt, a driving shaft, a driving roller thereon about which said narrow belt passes, rollers, one of same having a worm gear secured thereto engaging a worm on said driving shaft driving said wide belt, a speed reducing gearing on the shaft of one of the rollers of said wide belt 80 operatively connecting the roller with said driving shaft, an intermittently rotary transfer device above said narrow belt, and means for intermittently actuating said transfer device. 85

3. In connection with a bottle cap assembling machine comprising a rotary finishing head, the combination of a delivery mechanism consisting of a narrow conveyor belt 90 running with a speed substantially corresponding to the angular speed of the finishing head and being laterally disposed to the same so as to receive the assembled caps dropping from the said finishing head, a wire conveyor belt, running at lower speed than the narrow belt and at a right angle to the same, having one end closely adjacent to the narrow belt, a driving shaft, a driving roller thereon, about which said narrow belt passes, 95 rollers, one of same having a worm gear secured thereto engaging a worm on said driving shaft driving said wide belt, a speed reducing gearing on the shaft of one of the rollers of the same, operatively engaging said shaft, an intermittently rotary transfer device above said narrow belt, a plurality of means actuated in synchronism with the driving roller of said low speed belt, and means co-operating therewith and with said transfer device for intermittently actuating said transfer device. 100

4. A delivery mechanism for bottle cap assembling machines embodying therein a narrow, high speed conveyor belt extending laterally of an assembling machine and adapted to receive completely assembled caps one at a time from the finishing head of said machine, a wide, low speed conveyor belt moving at right angles to the direction of movement of said high speed belt and 105

- movement of said high speed belt and having one end thereof closely adjacent thereto, a driving shaft, a driving roller thereon about which said high speed belt passes, a worm gear carried by one of the rollers about which said low speed belt passes, a worm carried by said shaft, co-operating with said gear, whereby said belts are simultaneously driven at a fixed ratio, a shaft 5 above said high speed belt, a plurality of spaced vanes extending longitudinally of said belt and adapted to form guiding means adjacent the opposite sides thereof, a ratchet wheel carried by said shaft, a swing arm 10 idly mounted to have movement concentrically with said ratchet wheel, a pawl carried by said swing arm, a crank shaft, a weight acting upon one of the cranks of said shaft, operative connections between said crank 15 and said swing arm, said pawl and said ratchet wheel being so set as to cause movement to be imparted to said vanes by said weight, a cam carried by said crank shaft, and a plurality of tappets carried by said 20 25 worm gear and co-operating with said cam, whereby said pawl will have a slow setting movement and a rapid feeding movement, and said vanes will be intermittently actuated to simultaneously remove caps in 30 groups from said high speed belt and deliver them to said low speed belt.
10. A delivery mechanism for bottle cap assembling machines embodying therein a narrow, high speed conveyor belt extending laterally of an assembling machine and adapted to receive completely assembled caps one at a time from the finishing head of said machine, a wide, low speed conveyor belt moving at right angles to the direction of movement of said high speed belt and having one end thereof closely adjacent thereto, a driving shaft, a driving roller thereon about which said high speed belt passes, a worm gear carried by one of the rollers about which said low speed belt passes, a worm carried by said shaft, co-operating with said gear, whereby said belts are simultaneously driven at a fixed ratio, a transfer device about said high speed belt, a plurality 40 45 50 55 60 of members carried by said worm gear, means co-operating therewith and with said transfer device for intermittently actuating said transfer device, whereby caps upon said high speed belt will be simultaneously removed therefrom in groups and delivered to said low speed belt, and a speed reducing gearing between said driving shaft and the main shaft of a bottle cap assembling machine.
11. A delivery mechanism for bottle cap assembling machines embodying therein a narrow, high speed conveyor belt extending laterally of an assembling machine and adapted to receive completely assembled caps one at a time from the finishing head 65 of said machine, a wide, low speed conveyor belt moving at right angles to the direction of movement of said high speed belt and having one end thereof closely adjacent thereto, a driving shaft, a driving roller thereon about which said high speed belt passes, a worm gear carried by one of the rollers about which said low speed belt passes, a worm carried by said shaft, co-operating with said gear, whereby said belts are simultaneously driven at a fixed ratio, a shaft 70 75 80 85 90 95 above said high speed belt, a plurality of spaced vanes extending longitudinally of and equidistantly located around said shaft and adapted to form guiding means adjacent the opposite sides thereof, a ratchet wheel carried by said shaft, a swing arm idly mounted to have movement concentrically with said ratchet wheel, a pawl carried by said swing arm, a crank shaft, a weight acting upon one of the cranks of said shaft, operative connections between said crank and said swing arm, said pawl and said ratchet wheel being so set as to cause movement to be imparted to said vanes by said weight, a cam carried by said crank shaft, a plurality of tappets carried by said 100 105 110 115 120 125 worm gear and co-operating with said cam, whereby said pawl will have a slow setting movement and a rapid feeding movement, and said vanes will be intermittently actuated to simultaneously remove caps in groups from said high speed belt and deliver them to said low speed belt, and a speed reducing gearing between said driving shaft and the main shaft of a bottle cap assembling machine.
12. A delivery mechanism for bottle cap assembling machines embodying therein a narrow, high speed conveyor belt extending laterally of an assembling machine and adapted to receive completely assembled caps one at a time from the finishing head of said machine, a wide, low speed conveyor belt moving at right angles to the direction of movement of said high speed belt and having one end thereof closely adjacent thereto and upon a lower plane than the upper reach of said high speed belt, a stay rod extending parallel with said high speed belt and having an inclined surface leading toward said low speed belt, means adapted to simultaneously actuate said belts, a transfer device above said high speed belt, and means for intermittently actuating said transfer device, whereby caps upon said high speed belt will be simultaneously removed therefrom in groups and delivered to said low speed belt.
13. A delivery mechanism for bottle cap assembling machines embodying therein a narrow, high speed conveyor belt extending laterally of an assembling machine and adapted to receive completely assembled caps one at a time from the finishing head of said

machine, a wide, low speed conveyor belt moving at right angles to the direction of movement of said high speed belt and having one end thereof closely adjacent thereto and upon a lower plane than the upper reach of said high speed belt, a stay rod extending parallel with said high speed belt and having an inclined surface leading toward said low speed belt, a driving shaft, a driving roller thereon about which said high speed belt passes, a worm gear carried by one of the rollers about which said low speed belt passes, a worm carried by said shaft, co-operating with said gear, whereby said belts are simultaneously driven at a fixed ratio, a shaft above said high speed belt, a plurality of spaced vanes extending longitudinally of and equidistantly located around said shaft and adapted to form guiding means adjacent the opposite sides thereof, a ratchet wheel carried by said shaft, a swing arm idly mounted to have movement concentrically with said ratchet wheel, a pawl carried by said swing arm, a crank shaft, a weight acting upon one of the cranks of said shaft, operative connections between said crank and said swing arm, said pawl and said ratchet wheel being so set as to cause movement to be imparted to said vanes by said weight, a cam carried by said crank shaft, and a plurality of tappets carried by said worm gear and co-operating with said cam, whereby said pawl will have a slow setting movement and a rapid feeding movement, and said vanes will be intermittently actuated to simultaneously remove caps in groups from said narrow belt to said wide belt.

15. The combination with a bottle cap assembling machine having a finishing head, of a frame forming a lateral extension to said machine beginning at said head, a narrow, high speed conveyor operatively mounted in said frame transversely thereof and commencing adjacent said finishing head to receive therefrom and carry away completely assembled caps, a transfer device operatively mounted in said frame above said conveyor and adapted when actuated to remove a group of caps therefrom simultaneously with the operation of said conveyor, means for intermittently actuating said transfer device, and a wide, low speed conveyor operatively mounted in said frame longitudinally thereof and commencing adjacent said high speed conveyor to receive groups of caps therefrom and carry them away.

16. In a device of the class described, the combination of a frame, a driving shaft supported therein and provided with a worm and a roller, a parallel roller in said frame and a conveyor belt engaged about the same and also about said shaft roller whereby to be driven, a transfer device mounted in said frame and comprising shaft-supported circular head plates connected by vanes parallelizing said conveyor and adapted to sweep transversely thereacross, a worm gear meshing into said worm and provided with tappets, a crank shaft carrying a cam projecting into the path of said tappets whereby to be actuated, a ratchet carried by one of the head plates and a swing arm mounted on the shaft therefor and carrying a pawl in relation to the ratchet, connective means whereby actuation of the cam will cause engagement of the pawl with the ratchet, and a weight associated with said connective means to cause the actuation of the transfer device on each engagement of the pawl with the ratchet.

17. An attachment for a machine for making and assembling bottle caps comprising a delivery belt, means adapted to guide and actuate said delivery belt adjacent the assembly wheel of said machine, means adapted to cause the movement of the caps from the said assembly wheel to the said delivery belt, an examining belt, means adapted to guide and actuate the said examining belt more slowly than the delivery belt and at an angle to the said delivery belt and adjacent the said delivery belt, and means adapted to move the caps from the said delivery belt to the said examining belt.
18. In combination with a machine for making and assembling bottle caps having an assembly wheel, delivery means adapted to convey the caps from the said assembling wheel, examining means adapted to receive the caps from the said delivery means, and means adapted to be intermittently operated by the movement of the said assembly wheel for moving the caps from the said delivery means to the said examining means.

In witness whereof I have hereunto affixed my signature this 7th day of February, 1922.

BERTHOLD NAGY.
